UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

CURRENT COLLECTOR.

Original application filed March 1, 1922, Serial No. 540,147. Divided and this application filed May 1, 1924. Serial No. 710,467.

To all whom it may concern:

Be it known that I, SAMUEL S. MATTHES, a citizen of the United States of America, residing at Mansfield, in the county of Rich-
mond and State of Ohio, have invented cer-
tain new and useful Improvements in Cur-
rent Collectors, of which the following is a
specification.

My invention relates to electric current
collectors for moving vehicles and is par-
ticularly adapted to that class of vehicles
known as a trolley-bus and which operates
on the highway either directly below and in
line with the overhead conductors or to
either side thereof and in line with the con-
ductors, and which is free to change this
direction of operation toward or away from
the overhead conductors at the will of the
operator. Such operation of the trolley-
bus is also known as trackless trolley op-
eration.

The object of my invention is to provide
a device which will collect current from two
overhead conductors of different polarity
and permit the vehicle or trolley-bus to
move about freely relative to the conductors
within reach of the trolley pole and main-
tain contact with the conductors. To the
attainment of this end and accomplishment
of other new and useful objects as will ap-
pear, the invention consists in the novel fea-
tures of construction, combination of the
parts and in the unique relation and dispo-
sition of the various parts hereinafter more
fully described and claimed and shown in
the accompanying drawing in which:

Fig. 1 is a top plan view of my invention
engaging the overhead conductors when the
trolley-bus is operating to one side of the
conductors.

Fig. 2 is a side view of my invention en-
gaging the overhead conductors and in
which the trolley-bus is operating below and
in line with the conductors.

Fig. 3 is an end view of Figs. 1 and 2.
This application is a division of my co-
pending application, Serial No. 540,147,
filed March 1, 1922.

In my preferred form I employ a trolley
pole or support 1 mounted upon the trolley-
bus in the usual manner well known in the
art and to the upper end of the support is
secured a member 2 provided with a clevis
3. Mounted in the clevis is an insulating

member 4 and secured to the clevis by the 55
bolt and nut 5. To each end of the insulat-
ing member 4 is secured a current collecting
element 6 and secured to the insulating ele-
ment by means of integrally formed yoke
7 and the bolt 8.

The member 2 is rigidly secured to the
member 1, but the insulating member 4 is
pivotally mounted in the yoke 3.

The current collecting members 6 com-
prises a horizontally disposed element 9 the 65
upper surface of which forms a convex sur-
face 10 adapted to engage the conductors
11-11' respectively, and also having an
upstanding flange 12, the outer surface
13 of which is of circular formation, all
70 points of which in any single horizontal
plane are equally distant from the pivoted
point A. The surface 13 is preferably ob-
liquely disposed in order that interference
with the trolley clamps, ears, etc. used in
75 supporting the trolley conductor may be
avoided.

The members 9 are so shaped that the dis-
tance B is less than the distance C which is
preferable on account of the convex forma-
tion of the surface 10. It will be observed
80 that if the pole 1 is caused to take an an-
gular formation to either side of the longi-
tudinal direction with respect to the trolley
conductor, that the flanges 13 will maintain
the center A substantially midway between
85 the conductors 11 and 11', and that since
the exterior surface of the flange 13 is
formed with equal radii in any single hori-
zontal plane about the point A that the 90
trolley-bus to which the device is secured
can readily swing from one side to the other
from a direct line of operation below the
trolley wire and without bringing any un-
due strain upon the conductors in tending
95 to throw them toward or away from each
other. It is also necessary to meet condi-
tions where the angularity of the support
member 1 changes with respect to the con-
ductors due to variations in the height of
100 the conductors above the ground. I meet
this condition by having the surface 10 of
a convex formation relative to the conductors
as already pointed out above and this
permits me to mount the insulating member
105 4 to the pole with only a single motion rel-
ative thereto; namely, the pivoting of the
member 4 about the axis of the member 5

which pivotal motion is necessary in order to allow for variations in height of one conductor relative to the other.

To the best of my knowledge all previous constructions of this class have employed the small so-called trolley-wheel or sliding shoe of limited size engaging each conductor, but these devices are very readily thrown from the conductors and I have attempted to overcome this difficulty by the construction herein set forth and beyond doubt many modifications will suggest themselves to one skilled in the art.

I claim:

1. A current collecting device comprising a support member, a head adapted to swing in a substantially vertical plane, a pair of current collecting members supported by the head and means to insulate the collecting members from each other; each collecting member comprising a horizontally disposed flange, the upper surface being convex to a substantially horizontal plane and having an upstanding flange the outer surface being convex to a substantially vertical plane.

2. A current collecting device to engage a pair of parallel conductors comprising a support and a pair of collecting members pivotally mounted on the support to swing in a plane pierced by the axis of the support and insulated therefrom; each collecting member comprising a flange having a surface contacting with a conductor and con-

vex thereto and a second flange projecting from the first flange and engaging the inner surface of a conductor to prevent lateral displacement of the collecting device; the engaging surface of the second flange being convex to the conductor.

3. A current collecting member to engage an overhead conductor comprising a flange having an arc shaped formation, a flange projecting from the convex face of the first flange and having a convex face, the convex faces of the two flanges forming an angle to receive the overhead conductor, and means to secure the collecting device to a support and in pivotal relation thereto in a plane pierced by the axis of the support.

4. A current collecting device to engage a pair of conductors comprising a supporting pole, a transverse head mounted on the pole to pivot in a fixed plane pierced by the axis of the pole and a pair of current collecting members mounted on the head; each collecting member provided with means having a surface convex to and engaging a conductor and changing its point of engagement with a change in the vertical angle of the supporting pole, each collecting member also provided with means forming a segment of a circle to engage a conductor and prevent lateral displacement of the collecting device.

In testimony whereof I affix my signature.

SAMUEL S. MATTHES.
